UNITED STATES PATENT OFFICE

MARTIN H. GAMBE, OF PAWLING, NEW YORK

FURNITURE

Application filed April 29, 1932. Serial No. 608,257.

This invention relates to improvements in furniture, particularly chairs of the knock down and foldable type. As an example of my improvements a chair of the outdoor, porch or lawn type, has been illustrated and is described in this specification.

One object of the present improvements is to provide a chair which can be easily assembled and disassembled by the user either for storage or transportation purposes and such assembling and disassembling may be accomplished simply by the insertion and removal of connecting pins at desired points.

A further object of my invention is to provide an article of furniture of the type described, which will not only be attractive in appearance, but easy to manufacture and inexpensive to the purchaser.

For a detailed description of this form of my invention reference may be had to the following specification and the accompanying drawing forming a part thereof, in which Fig. 1 is a perspective view of an improved chair; Fig. 2 is a side elevation thereof; Fig. 3 is a front elevation thereof; Fig. 4 is a side elevation of the chair when folded for storage or to occupy a small space; and Fig. 5 is a detailed view of the connecting devices.

Referring to the drawing, numeral 1 indicates the back of the chair which is preferably composed of a series of strips or slats connected together by cross pieces or bars 2. The back 1 includes lateral side strip 3 to which hinged connectors 4 and 5 are attached. These connectors may be fixed in position by screws or other suitable means, detached portions of the connectors being shown in Fig. 5. The connecting parts 5 are secured to the lower ends of the lateral side bars 3 which are thereby connected to the rear legs. The legs or base of the chair preferably comprise two angular pieces consisting of the parts 6 and 6' which are connected by transverse bars 7 and 7'. These legs are pivotally and preferably detachably connected together at their upper inner ends by means of connecting pieces 8 and 8' similar to those shown in Fig. 5. Located centrally on the rear legs are connecting parts 5' which are adapted to engage the connecting parts 5 on the lower ends of the

lateral strips 3 of the back 1. The numerals 9 and 9' indicate the arm portions of the chair, the rear ends of which have the connecting parts 10 adapted to engage the connecting parts 4 on the lateral strips 3 of the back 1. The arms 9 and 9' are attached to the front surfaces of the forward legs by means of the hinged connecting pieces 15 and 15'. Said hinged connections, 4 and 10, and 15 and 15' form the sole connections between said arms and the frame of the chair.

The seat of the chair consists of the strips 11 which are connected together by the transverse cleats 12. The rear ends of the strips 11 are provided with connecting pieces 13 which engage complementary connecting pieces 13' on the cross bar 7.

Beneath the forward portion of the strips 11 are connecting pieces 14 which engage complementary connecting pieces 14' on the cross bar 7.

The details of the connecting parts above referred to are illustrated in Fig. 5. These consist of two hinge-like plates 16 and 17 which are adapted to be secured together by means of a removable pin 18 having a knob or projection 19 on one end so that it may be easily grasped by the operator. The latter knob obviously may be omitted when necessary and is desired to permit the parts to be hinged together without embodying the removable feature.

From the above description it will be seen that by removing the pins from the connecting pieces 4-10 and 13-13' the chair may be collapsed into the form substantially shown in Fig. 4. This easily adapts the chair for storage in a small place, such as a closet, while the remaining connecting parts form hinges on which the elements of the chair may turn. On the other hand, by removal of all of the pins between the connecting parts which secure the elements of the chair in position, the chair may be completely disassembled and the parts superposed on each other for insertion in a small box or carton in order to be easily transported from one place to another.

I have found that for a normal size chair such a box or carton may be provided that is

approximately 32 inches square and 8 inches deep.

Having thus described this form of my invention, what I claim and desire to protect by Letters Patent is:

Furniture of the type described, comprising seat, arm, back and leg members formed of wide strips of suitable material, and being detachably connected together by hinges, the front and rear leg members being hinged together at their upper transverse inner edges, the back member having its outer strips hinged to the wider surfaces of said rear leg members, transverse bars connecting the front leg members and the rear leg members, respectively, said seat being removably connected with said front transverse bar and said rear transverse bar, and strips forming said arms and hinged to the upper front surfaces of the front leg members and to said strips forming the back, said hinges forming the sole connection between said arms and the adjacent parts of the chair, and certain of said hinges having removable pins to afford detachability of the parts to which they are attached.

Signed this 28th day of April, 1932.

MARTIN H. GAMBEE.
